Primary Examiner — T. Chase Nelson(74) Attorney, Agent, or Firm — Eaton & Van Winkle LLP; Robert D. Katz, Esq.(57) CLAIM

The ornamental design for a shoe with decorative sole, as shown and described.

DESCRIPTION

FIG. 1 is a bottom perspective view of the shoe with decorative sole having a camouflage, rhinestone pattern;

FIG. 2 is a bottom plan view thereof;

FIG. 3 is a top plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines are for purposes of illustrating portions of the shoe that form no part of the claimed design.
